CLAIM

The ornamental design for a four-wheeled cart folding connector as shown and described.

DESCRIPTION

FIG. 1 is a top perspective view of a four-wheeled cart folding connector showing my new design;

FIG. 2 is a bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an enlarged view of a portion labeled as "9" on FIG. 1; and

FIG. 10 is another top perspective view, showing the four-wheeled cart folding connector in a closed configuration; and,

FIG. 11 is an environment perspective view of the four-wheeled cart folding connector, showing in a state of use. The long dash-short dash broken lines depict enlargement boundaries that form no part of the claim. The evenly-spaced broken lines illustrate portions of the four-wheeled cart folding connector that form no part of the claimed design. The evenly-spaced broken lines in FIG. 11 are for the purpose of illustrating environment of the four-wheeled cart folding connector and form no part of the claimed design.

1 Claim, 11 Drawing Sheets
